PAPER DRIVE MEANS FOR ADDING MACHINES

Max Garbell, Chicago, Ill., assignor to Victor Adding Machine Company, Chicago, Ill., a corporation of Delaware

Application July 15, 1936, Serial No. 90,697

4 Claims. (Cl. 197—128)

This invention relates to paper drive means for adding machines, and is more particularly directed to means for feeding papers independently of the platen.

5 Heretofore, multiple strips of paper have been employed, which were fed simultaneously by the platen, resulting in a rather hard operation of the machine, and the present invention is directed to a solution of this problem. It is also 10 directed to means for selectively conditioning the drive means to move one of the papers a greater distance than the normal feed.

The chief object of the invention is to provide an improved paper drive for adding machines, and the like.

Another object is to provide simple and efficient means for feeding multiple strips of paper independently of the platen, and for positively feeding one paper upon the operating stroke 20 of the machine, and to feed another paper upon the restoring stroke of the machine.

And a further object is to provide means for conditioning the drive means to feed one paper a greater distance than its normal feed.

25 Other objects and advantages will become apparent from the specification and drawings.

Referring to the drawings:

Figure 1 is a longitudinal partial sectional view of an adding machine, showing my invention applied thereto.

Figure 2 is a view similar to Figure 1, showing a changed position; and

Figure 3 is a cross-sectional view taken on the line 3—3 of Figure 1.

35 The invention is shown as applied to a Victor adding machine, and only the parts more particularly associated with the present invention have been illustrated and described.

The machine is originally provided with a 40 rocker plate 10 which is pivotally carried on the side plates 11 and 11a by means of studs 12. The rocker plate is connected to an upright member 13 carried for reciprocating movements in bearings 14 and 15 secured to the side plate 11.

45 This upright member 13 is operatively connected to the actuator shaft 16 of the machine, by means of a bell-crank 17 carried by a stud 18 on the side plate 11, and has a leg 19 provided with an elongated slot 20 which receives a pin 21 secured in the upright member 13. The other leg 22 of the bell-crank 17 is connected to a link 23 by a pin 24 and the other end of the link is connected by a pin 25 to an arm 26 fixed to the actuator shaft 16. The rocker plate 10 normally carries a pawl 27 pivoted thereto, at 28,

and which is urged by a spring 29 into engagement with a ratchet-wheel 30 secured to the platen 31, carried on a shaft 32 in the side plates 11 and 11a. This pawl 27 serves to rotate the platen for a step-by-step movement in the usual manner, but in this instance, it merely serves to present different portions of its surface to receive the impact of the type bars (not shown) and the paper drive means is independent of the platen, as will be presently described.

10 The rocker plate 10 is provided with ears 10a which carry a pawl 33 on a pin 34, and a spring 35 urges the pawl into engagement with a ratchet-wheel 36 that is fixed to a feed roll 37 carried on a shaft 38 supported in the side plates 11 and 11a. The feed roll 37 has a companion roll 39 carried on a shaft 40 which is also supported in the side plates 11—11a, and receives a record strip therebetween, to feed the same. The feed roll 37 also has a sprocket gear 41 fixed thereto and a chain 42 that extends to a sprocket wheel 43 fixed to a take-up roll 44 carried on a shaft 45 supported in the side plates 11 and 11a. Between the take-up roll 44 and the side plate 11 is a friction clutch 46, which 20 compensates for the increasing size of the take-up roll in the usual manner, as the record strip is wound therearound.

The record strip roll A on which a permanent record is kept, is carried on a shaft 47 supported 30 in the side plates 11 and 11a, and the free end of the record strip is guided over a plate 48 and extends through an opening 48a therein and under an arcuate portion 48b thereof that is positioned below and in spaced relation with the 35 platen 31. The free end of the record strip also passes in front of the platen over a paper table 49 and through a guide member 50, and between the feed roll 37 and its companion roll 39, to the take-up roll 44.

40 Another paper roll B, which is adapted to serve as receipt slips when severed, is carried on a shaft 51 supported in the side plates 11 and 11a, with the free end thereof directed between a feed roll 52 and a companion roll 53, and extends in front of the platen 31 over the record strip and through the guide member 50. The feed roll 52 is supported on a shaft 54 carried in the side plates 11 and 11a below the platen 31, and has a ratchet-wheel 55 fixed thereto which is normally engaged by a pawl 56 pivotally carried at 57 on an arm 58 that is pivotally carried on a stud 59 secured to the side plate 11. The pawl 56 is normally urged into engagement with the ratchet-wheel 55 by a spring 60, and 55

the arm 58 is normally urged upwardly by a spring 61 fixed thereto, and which extends around the stud 59 and is secured at 62 to the side plate 11. The arm 58 is in the form of a 5 beli-crank and has an integral upwardly extending portion 63 which is urged by the spring 64 into engagement with a depending arm 66 extending from the rocker plate 10. The arm 58 is provided with an extension 65 at its free 10 end portion that is adapted to engage a slide 66 carried on the side plate 11 under the control of a depressible key 67. The slide 66 is provided with elongated slots 68-68 adjacent each end thereof through which the studs 69-69 extend 15 and which studs are secured to the side plate 11. The slide 66 is also provided with a cam slot 70 which receives a follower 71 secured to the stem 72 of the key 67, which is guided at its upper portion in a plate 73 of the keyboard 20 of the machine, and its lower end is guided on a stud 74 that extends through a vertical slot 75 in the stem 72 of the key. The stem 72 of the key 67 is also provided with a lip 76 that is adapted to be engaged by a pawl 77 pivotally 25 carried on the side plate 11, by a pin 78, and which pawl is urged toward the stem 72 by means of a spring 79. This pawl 77 is in the form of a bell-crank and has a depending member 80 pivotally carried thereon at 81, and normally depends into the path of an upwardly extending 30 ear 82 on the link 23.

Upon the movement of the actuator shaft 16, the link 23 is carried forwardly, which rocks the bell-crank 17 and forces the upright member 13 upwardly to rock the rocker plate 10 and carries the pawl 33 upwardly therewith to effect a turning movement of the ratchet-wheel 36 and feed roll 37, with the companion roll 39 to feed the record strip and through the chain 42, will 35 effect a turning movement of the take-up roll 44. The upwardly rocking movement of the rocker plate 10 carries the depending arm 64 therewith for a counter-clockwise movement away from the upwardly extending portion 63 of the arm 58, as 40 shown in dotted lines Fig. 1, and the arm 58 will be urged upwardly by its spring 61 until the extension 65 thereof engages the slide 66. During 45 this upward movement of the arm 58, the pawl 56 will ratchet against the ratchet-wheel 55 without effecting its turning movement and a turning movement of the feed roll 52. Upon the 50 restoring movement of the actuator shaft 16, the link 23 will be carried rearwardly to its normal position and rock the bell-crank 17 downwardly 55 which will carry the upright member 13 downwardly therewith to restore the rocker plate 10 to its normal position and carry the pawl 33 thereon for a ratcheting movement against the ratchet-wheel 36 without effecting movement of the record strip A. The restoring movement of 60 the rocker plate 10 carries the depending arm 64 therewith for a clockwise movement to engage the extending portion 63 of the arm 58 and effect a downward rocking movement of this arm 58 65 with the pawl 56 thereon to turn the feed roll 52 and companion roll 53 to effect a feed of the paper B.

This paper drive means is especially adapted for use in machines where it is desired to retain a permanent record of transactions, and wherein a duplicate of the transaction may be severed independently of the permanent record.

The key 67 serves to condition the paper drive means to effect a greater movement of the paper B than is effected during its normal movements.

As the key 67 is depressed, the follower 71 on the stem 72 thereof, will effect a sliding movement of the slide 66 by engagement with a cam slot 70 therein, to position the same out of the path of the extension 65 on the arm 58 and permit this 5 arm to be urged upwardly by its spring 61, as shown in full lines Fig. 2. When the arm 58 is in this upward position, the movement of the depending arm 64, upon the restoring movement of the rocker plate 10, will then effect a greater 10 movement of the arm 58 and pawl 56 to rotate the feed roll 52 a greater distance which will feed the paper B a greater distance than its normal movements. When the key 67 is depressed, (Fig. 2), the pawl 77 will engage the extension 76 of 15 the key stem 72 and withhold the key in depressed position with the slide 66 out of the path of the extension 65 on the arm 58. As the actuator shaft 16 is restored to its normal position, the link 23 is carried therewith, and the ear 82 on 20 the link will engage the depending portion 80 on the pawl 77 and effect a rocking movement of the pawl to release the same from the extension 76 of the key, and permit the key to be restored by its spring 83 to normal position, with the slide 66 25 again positioned in the path of the extension 65 on the arm 58. It will be noted that the ear 82 trips the pawl 77 to release the key and slide at the time the arm 58 has been forced downwardly below the slide 66 by the depending portion 64 of 30 the rocker plate 10, so that the slide 66 is then in the position shown in Fig. 1, to limit the normal movements of the arm 58 and pawl 56 to feed the paper B the same distance that the paper A is fed.

The paper B is retained against the feed roll 52 by the companion roll 53, which has its shaft 53a journaled in a pair of arms 53b carried adjacent the side plates 11-11a on a shaft 53c. These arms 53b each have a spring 53d fixed 40 thereto and to the side plates 11-11a, to maintain a constant pressure of the companion roll 53 against the feed roll 52. The shaft 53c has a lever 53e fixed to one end thereof, which is manually gripped to rock the companion roll 53 away 45 from the feed roll 52 to insert the paper B therefrom.

With this arrangement of the paper drive means, the record strip A and the paper B are fed in front of the platen 31 and independently 50 thereof, and the platen is partially rotated upon each operation of the machine to expose a different surface thereof to receive the impact of the type bars (not shown).

While the record strip A and paper B are positioned one in front of the other to be simultaneously printed upon with each operating stroke of the machine, the record strip A is fed upon the forward stroke of the actuator shaft and the paper B is fed upon the restoring stroke of the 60 actuator shaft.

I claim:

1. A machine of the class described having a platen, means for feeding two paper strips over and independently of said platen, said means comprising mechanism for feeding one of the paper strips in one direction of movement thereof and for feeding the other paper strip in the other direction of its movement, and key means controlling the movements of the mechanism to permit the last-mentioned paper strip to be fed a greater distance thereby.

2. A machine of the class described having a platen, means for feeding two paper strips about and independently of said platen, said means

comprising mechanism operable upon the operating stroke of the machine for feeding one of said papers and for feeding the other of said papers upon the restoring stroke of said machine, a depressible key, said mechanism being normally controlled by said key to feed said last-mentioned paper the distance said first-mentioned paper is fed, and for effecting the release of said mechanism to feed said last-mentioned paper a greater distance than the first-mentioned paper when said key is depressed.

3. A machine of the class described having a platen, means for feeding two superposed paper strips over and independently of said platen, said means comprising mechanism for feeding one of said paper strips upon the operating stroke of the machine and for feeding the other of said paper strips upon the restoring stroke of the machine, a depressible key, said key normally co-operating with said mechanism to provide a uniform feed of the paper strips and to control said

mechanism when depressed to condition the same for a greater feed of one of the paper strips.

4. A machine of the class described having a platen and a driving mechanism, means for feeding two paper strips independently of said platen, said means comprising drive rolls above and below said platen, a rocker plate under the control of the driving mechanism, pawl and ratchet means operatively connected with the rocker plate and coacting with said drive rolls for feeding the paper strips upon a complete operation of the operating mechanism, a depressible key, said key normally controlling the pawl and ratchet means to control the drive roll below the platen for a uniform movement with the drive roll above the platen, said key when depressed conditioning the pawl and ratchet means for a greater distance of movement to provide a greater distance of movement of said first-mentioned roll.

MAX GARBELL.
